FLASH PHOTOGRAPHY

Harold Eugene Edgerton, Belmont, Mass.

Application December 17, 1941, Serial No. 423,344

3 Claims. (Cl. 240—2)

The present invention relates to flash-photography, and more particularly to electrical flash-photography in which charged condensers are rapidly discharged through gaseous-discharge flash-lamps.

In the studio, as all conveniences are available, it is possible to supply the power necessary for purposes of such electrical flash-photography from the electrical wiring of the room. In the field, such as in news work, it often occurs that electrical power is unavailable for operating lamps of the above-described character.

An object of the present invention is to improve upon photographic field equipment, in order to enable the field photographer to enjoy the advantages of electrical flash-photography employing gaseous-discharge flash-lamps comparable to those obtaining in the studio.

The use of chemical flash-bulbs has long been recognized as attended with a number of inconveniences resulting from the delay involved in removing one bulb and replacing it by another. Proposals have therefore been made to employ incandescent bulbs, but they have never been successful and, in fact, have constituted steps backward rather than forward.

Another object of the present invention, on the other hand, is to provide a field system employing gaseous-discharge flash-lamps.

Other and further objects will be explained hereinafter and will be particularly pointed out in the appended claims.

With the above ends in view, a feature of the invention resides in mounting upon a portable field camera an electrically operated gaseous-discharge flash-lamp, in combination with a self-contained storage battery and a vibrator for converting the power of the battery into alternating current, and with means for reconversion into direct current for charging the condenser. Provision may also be made for operation from an alternating-current source, if desired, and for recharging the battery.

The invention will now be described more fully in connection with the accompanying drawings, in which Fig. 1 is a perspective illustrating a preferred embodiment thereof; Fig. 2 is a simplified circuit diagram omitting the battery source of energy and its connections; and Fig. 3 is a more complete circuit diagram.

A gaseous-discharge flash-lamp 18 disposed, together with a high-voltage spark trigger-wire or trip-wire flashing electrode 17, in an elongated light-permeable glass-bulb protective jacket or envelope 92, is shown mounted in a

reflector 25 upon an arm 63. An external triggering electrode 17, as shown, is necessary with the larger flash-lamps and at the higher voltages. Internal triggering electrodes may, however, be employed with shorter flash-lamps and lower voltages. The flash-lamp 18 may, if desired, be of the helical or spiral gas-filled type disclosed in Letters Patent 2,277,698, issued to Kenneth J. Germeshausen on March 31, 1942, and may be 10 easily interchanged in the reflector 25 by means of a plug-in base 94.

The reflector 25 extends forward from a lamp housing 26 to which the upper end of the arm 63 is directly secured. The lamp housing 26 15 carries a terminal board 104 (shown by dotted lines in Fig. 3) provided with plug receptacles 150, 152 and 171, 172 for receiving plugs 102 and 106, respectively. A plug 102, that is adapted to be plugged into the plug receptacles 150, 152 20 is connected to a camera-shutter synchronization switch 65. A plug 106, that is adapted to be plugged into the plug receptacles 171, 172, is connected to the coil of a trip magnet 67. The plugs 102 and 106 may thus be disconnected 25 from the terminal board 104 of the housing 26 on the arm 63 to facilitate packing the equipment in carrying cases. The lower end of the arm 63 is shown attached to the upper wall of a portable camera 35 that may be carried in the 30 field-photographer's hand.

The bulb 92 containing the flash-lamp 18 may, of course, be mounted upon the camera 35 without the reflector 25, but the reflector is especially desirable for field work, as it helps concentrate the light rays upon the object to be photographed and reduces the size of the flash-lamp necessary to be employed.

The assembly of the flash-lamp 18 and the reflector 25 in which it is housed may be mounted readily on almost any type of camera by means of the arm 63. The reflector 25 may be so oriented upon the camera 35 as automatically to illuminate the area desired to be photographed with relative uniformity at the moment of the 40 exposure flash. The reflector may be adjusted, for spot or flood lighting, by means of a knob 7 on the back of the lamp housing 26.

The flash-lamp 18 is controlled by a control circuit that is disposed, with a power unit and 50 other apparatus, in a box 41 that may be carried over the field-photographer's shoulder by means of a shoulder strap 43. The box 41, power-unit and all, may weigh only twenty pounds. It may be nine inches long, five inches wide, and nine inches high. The box 41 contains

apparatus and circuits diagrammatically indicated within the dotted-line outline 41 of Fig. 3, and described more fully hereinafter. The flash-lamp 18 and its connecting parts may be connected to, and disconnected from, the power-unit box 41 by means of a connector plug 55 that may be connected into an outlet connection 57 provided in the wall of the box 41. A six-foot cord 89 for containing the wiring is shown permanently attached to the lamp house 26 at one end and to the plug 55 at the other. A complete self-contained portable equipment is thus provided, that may be carried from place to place for photographing any object anywhere.

The control circuit contains a flash condenser 11, across which the flash-lamp 18 is connected. The exposure flash is produced by discharging the condenser 11 through the flash-lamp 18, in response to suitable energization of the trip-wire electrode 17, by means of a flash-lamp triggering circuit more fully described hereinafter. The discharge circuit for the condenser 11 through the flash-lamp 18 may be traced from a grounded terminal 15, at one side of the condenser 11, by way of a conductor 31, through the connection 57 and the flash-lamp 18, and by way of a conductor 29, through the connection 57, to the other side of the condenser 11.

A suitable source of direct-current energy must, of course, be provided for charging the condenser 11. As the instrument must be portable, no reliance can be placed upon outside sources of current. According to a feature of the invention, a small spill-proof lead storage battery 69, which may be of four volts, may be provided for operating the flash-lamp 18. This is small enough so as not to interfere with the portability of the instrument.

As a source of alternating-current energy or its equivalent is also needed, a vibrator inverter 39 is added, connected to a high-ratio step-up transformer 45, provided with a primary winding 47 and a secondary winding 49. The primary winding 47 is connected to the battery 69 through the vibrator 39. The voltage of the battery 69 is thus converted in the primary winding 47 into an interrupted or pulsating chopped wave, which is stepped up in the secondary winding 49.

The secondary winding 49 is connected to the condenser 11 through a rectifier 72. The stepped-up pulsating wave in the secondary winding 49 becomes thus converted into direct current for charging the flashing condenser 11. If the secondary winding 49 has a high impedance, it may perform also the current-limiting function for which a separate charging resistor or other impedance is normally supplied between the secondary winding 49 and the charging condenser 11.

Energy from the battery 69 is thus supplied to the flashing condenser 11, to charge the same, through the transformer 45. Energy from the same battery 69 may be provided for heating the cathode 79 of the rectifier 72. To this end, the cathode 79 may be connected by conductors 117 and 123 in circuit with a winding 83 that constitutes a further secondary winding for the primary winding 47 of the transformer 45.

If a suitable source of alternating current, such as the ordinary 110-volt, 60-cycle house mains, is available, however, the condenser 11 may be charged therefrom by plugging at 71. This may be effected by disconnecting the battery 69, even removing it altogether, if desired. The plug 71 is connected by input wires 73 to a jack 76 which, in turn, is connected to the secondary winding 49 75

of the same transformer 45, but employing a different primary winding 75. The jack 76 is connected by conductors 133 and 137 to the primary winding 75.

5 A condenser 135 is connected to the transformer to aid the vibrator during commutation by changing the power factor. Sparking at the vibrator contacts is thereby reduced.

10 A large-enough condenser 11 should be employed so as to impress sufficient power, under suitable voltage, between the cathode and the anode of the flash-lamp. There is no difficulty, through the medium of this apparatus, charging the condenser 11 to a voltage of, say, 2000 volts. 15 At this voltage, a condenser of 28 microfarads is very efficient.

A normally non-conducting gaseous-discharge trigger tube 1 for tripping the flash-lamp 18 may be connected to terminals 15 and 13, across an impedance 81, shown as a bleeder resistor. The bleeder resistor 81 is connected, in series with a bleeder resistor 82, across the condenser 11, which thus, by supplying energy to the bleeder resistor 81, constitutes the main power-supply for the tube 1. The resistors 81 and 82 may be so proportioned that a desired voltage of, say, 300 volts shall appear across the terminals 13 and 15 of the resistor 81.

The tube 1 may be of the cold-cathode gaseous-discharge type illustrated and described in Letters Patent 2,185,189, 2,201,166 and 2,201,167, issued to the said Kenneth J. Germeshausen, on January 2, 1940, and May 21, 1940. It may comprise an evacuated glass envelope containing several electrodes, namely, a solid cathode 2, an anode or plate 5, and one or more grids, inner and outer grids being shown at 3 and 4, between the anode 5 and the cathode 2. As explained in the said Letters Patent, the source of the electrons is a bright cathode spot on the surface of the cathode 2. Part of the impedance 81 is shown connected between the cathode 2 and the grid 4. The cathode 2 and the grid 3 may be connected together, with or without a further impedance (not shown) between them.

40 A trigger-discharge circuit for a condenser 40 is also connected to the terminals 13 and 15, in parallel with the tube 1. One side of the condenser 40 is connected in this discharge circuit to the terminal 13. The other side of the condenser 40 is connected, by way of a conductor 90, to the primary winding 74 of a transformer 36 and, by way of the conductor 27, to the ground terminal 15. The condenser 40 is thus connected in this discharge circuit in series with the primary winding 74. One side of the secondary winding 38 of the transformer 36 is grounded to the terminal 15 by way of the conductor 27, and the other side is connected, by a conductor 37, to the trip-electrode 17. A return path is afforded by capacity coupling of the trip-wire electrode 17 to the flash-lamp 18. The condenser 40, therefore, becomes charged from the same direct-current source 45, 72, as the condenser 11, through the resistor 81 and the primary winding 74. The flashing circuit thus contains the flash-lamp 18 and the secondary winding 38, which operates as an induction coil.

45 A hand-controlled push-button switch 53 is shown in Fig. 1 mounted upon the box 41. The switch 53 is shown in Figs. 2 and 3 connected across the anode or plate 5 and the grid or control electrode 4, through a trip condenser 96 and a leak resistor 97, in parallel, by way of conductors 91 and 93. At any time after the direct-

current source 45, 72, charges the condenser 11 to its maximum value, the push-button switch 53 may be closed. The potential of the grid 4 will then become raised until the break-down voltage between the grid 4 and the cathode 2, or the grid 4 and the grid 3, is exceeded, whereupon the normally ineffective trigger-tube 1 becomes effective by being rendered conducting. Current then flows through the trigger tube 1, causing the condenser 40, which had become charged from the direct-current source 45, 72 simultaneously with the charging of the condenser 11, to discharge through its before-described trigger condenser-discharge circuit comprising the primary winding 14 of the transformer 38. A resulting voltage-surge pulse of the secondary winding 38 of the transformer 38 becomes thus impressed upon the trigger electrode 17 of the flash-lamp 18. This causes the gas in the flash-lamp to ionize, producing a conducting path through the flash-lamp 18, permitting the condenser 11 to discharge therethrough. The resulting high-voltage triggering spark through the flash-lamp 18 will yield a very brilliant exposure flash of extremely short duration. The time taken between the closing of the push-button switch 53 and the flash of light from the flash-lamp 18 is very brief. It is therefore possible to produce this very brilliant flash of light at any desired instant for taking photographs. When the condenser 11 is fully discharged, the flash-lamp 18 extinguishes, and the cycle is ready for repetition.

The operation of the synchronization switch 65 is effected in timed relation to the flashing of the flash-bulb 18 under the control of the push-button-switch 53. To this end, the plug receptacles 150 and 152, to which the synchronizing switch 65 is connected by the plug 102, are connected in parallel to the anode 5 and the control electrode 4. The connections may be traced from the conductor 91, that is connected to one side of the push-button switch 53 and to the control electrode 4, and by way of a conductor 6, through the connector 51, to the plug receptacle 152; and from the conductor 93, that is connected to the other side of the push-button switch 53 and to the anode 5, by way of the conductor 27, and through the connector 51, to the plug receptacle 150. The lamp 18 may thus be synchronized to flash at a time when the shutter is open. This is arranged by the use of a contact point which is operated when the shutter 66 is open. This may be either external or internal but is operated by the mechanism that opens the leaves of the shutter.

The shutter 66 may be operated independently of the push-button switch 53 by means of a push-button switch 51, that controls the coil of the trip magnet 67. The shutter may also be operated manually, or with the usual cable release. As illustrated in Figs. 2 and 3, the battery 69 is connected to the trip coil 67 by the closing of the switch 51. The connections may be traced from the negative end of the battery 69, by way of the conductor 101, through the connector 51, to the push-button switch 51, then through the receptacle 171 and the plug 106, the trip coil 67, and the receptacle 172 and the plug 106, by way of a conductor 8 and conductor 31, to the grounded positive terminal of the battery 69.

The flash-lamp 18 should have characteristics such as to produce an extremely rapid exposure. The rapidity of the exposure produced with the hereinafter described flash-lamp, indeed, far exceeds that of the fastest camera shutter.

A bright flash will be produced if the energy is expended in the flash, instead of being wasted elsewhere. The dimensions of the tube, the voltage employed with these dimensions, and the pressure of the gas in the tube, all are factors that determine the brightness of the flash. The influence of the dimensions will be understood when it is reflected that if the flash-lamp 18 is short, there will not be so much resistance between its cathode and its anode, through the gas in the tube, as when the lamp is large. The increased resistance produced by a long tube may have the same effect as the increased power afforded by a proper-size condenser.

The gap length, between the electrodes of the flash-lamp 18, may preferably be about 10 to 12 inches. It may, however, be longer, even as long as sixty inches. The diameter of the arc path also influences the effective resistance of the flash-lamp. If this diameter is reduced, the resistance of the lamp becomes increased. Under some conditions, more light is then produced. The internal diameter of the flash-lamp 18 may preferably be about $\frac{3}{8}$ to $\frac{1}{2}$ of an inch, but it may be as low as $\frac{1}{8}$ inch and as large as $\frac{3}{4}$ of an inch. In general terms, it may be stated that the length of the lamp should be at least ten times as long as its diameter.

The pressure of the gas in the flash-lamp depends, to some extent, upon the voltage. At higher voltages, speaking generally, either the gas pressure must be raised, or else the flash-lamp must be made longer. The lower the voltage, on the other hand, the shorter may be the length of the flash-lamp, or the lower may be the gas pressure. The diameter need not be substantially changed in response to these variations. The voltage may be as low as between about 200 or 300 volts, though a voltage as low as 110 volts has been used. The upper voltage limit may vary with the gas pressure and the length of the flash-lamp. Some particular types of flash-lamp will easily operate above 3000 volts.

Good results have been obtained at a gas pressure of 5 centimeters, but higher pressures have been used, even almost up to atmospheric. At 2000 volts, a pressure from $2\frac{1}{2}$ to 10 centimeters is workable.

There are also other factors, which can not be expressed mathematically, yet which have a bearing upon the efficient operation of the instrument. In a high-pressure lamp, the ionized vapor does not deionize at a rapid enough rate to produce a practical light-source at high frequency. The flash-lamp must not be permitted to become heated up too much; for if the lamp is operated at too high a temperature, it may either fail to ignite or, on the other hand, its arc may degenerate into a continuous glow, with only a very small-intensity consequently attendant continuous light. The voltage of the condenser 11 and the other factors before discussed should be properly chosen to prevent this happening.

The dimensions of the tube have a bearing also in connection with the temperature at which the lamp is operated. Very large tubes have a tendency to become automatically cooled between flashes. It is desirable that the ratio of the total over-all energy input to the ratio of the tube dimensions be maintained to an extent sufficient to produce proper flashing for stroboscopic or other purposes.

The gas contained in the flash-lamp 18 may be

krypton, but other gases are also suitable, particularly argon and xenon.

One advantage of employing krypton, argon and xenon as the gas filling of the tube is that the pressure of these gases does not change so rapidly with temperature as do other gases, like mercury vapor. This enables the lamp to be operated with high efficiency both when cold and when hot.

The volume of light of the exposure flash produced by the lamp 18 makes possible the use of small camera apertures with a resulting great depth of field. The flashes are unaccompanied, however, by eye discomfort, due to the color and shortness of the flashes.

Owing to its freedom from dependence on external lighting circuits, and the great capacity of the instrument before recharging the battery 69, the present invention makes it possible for the photographer to roam about, taking flash after flash, without taking heed to anything except pressing the shutter or the button 51 at the proper time. He is assured that he will have ample illumination to obtain natural, critically sharp photographs of large objects and small, whether stationary or moving at high speed, and all of equal photographic quality, as the flashes produced by the successive battery charges are of uniform intensity and volume. He may employ about any ordinary camera. The only necessary addition to his camera 35 is the flash-lamp 18, with or without the reflector 25 in which it is disposed, mounted on the camera, and the power unit contained in the box 41.

The power unit is shown provided with a further outlet 69 for connecting a second flash-lamp 61, where it is desired to obtain side lighting, as is sometimes desired in the field. The flash-lamp 61 may be connected in parallel to the flash-lamp 18, as illustrated in Fig. 3, and described more fully in a copending application, Serial No. 421,931, filed December 6, 1941. The parallel-connected wires may be contained in a fifteen-foot cord 30, connected at one end to the outlet 69 and at the other to a second lamp house 68 mounted upon a bracket. Reference numerals applied to the connections and other parts related to the flash-lamp 61 are the same as those described above, but augmented by 200. The reflector, for example, is shown at 225.

Provision has been made in the panel for venting the gases to the outside. The battery can be changed quite readily, since the terminals are accessible.

An electrical battery voltmeter 28 is provided on the top of the power unit for reading the voltage of the battery.

A four-position switch 87 on the top of the power-unit box 41 provides the following methods of operation: (1) off, (2) battery operation, (3) A. C. operation, (4) battery charge. The description above of the operation has been made on the assumption that the switch 87 occupies the "battery-operation" position.

The four-position switch 87 is provided with a shaft 44, integrally carrying four switch-arms 16, 12, 10 and 19, each adapted to occupy the four positions before mentioned. These switch arms are each adapted to engage four contact members in the respective four positions. Not all 70 these contact members, however, are effective to make connections.

In the "off" position, all four switch arms 16, 12, 10 and 19 engage respective contact members for opening all the circuits. In the "off" 75

position, accordingly, the circuits are all open.

In the "battery-operation" position, the switch arms 16 and 19 engage open-circuit contact members, thus disconnecting a full-wave copper-oxide rectifier 145, at the switch arm 19, and the input plug 71, at the switch arm 16. The switch arm 12, however, engages a contact member 100 and the switch arm 10 engages a contact member 103. In the "battery-operation" position, therefore, two connections are made. One connection completes a circuit from the negative terminal of the battery 69, by way of conductors 101 and 151, through the switch arm 10 of the switch 87, the contact member 103 in contact therewith in this position and, by way of a conductor 105, to the vibrating member of the vibrator inverter 39. The stationary members of the vibrator inverter 39 are connected by conductors 107 and 109 to different taps of the primary winding 47. An intermediate tap 111 is connected by a conductor 113 to the grounded positive terminal of the battery 69. One of the connections completed in this position of the switch 87, therefore, is from the battery 69 to the primary winding 47 of the transformer 45, through the vibrator inverter 39. A magnet coil 115 causes the vibrator 39 to vibrate. The other connection made in this position of the switch 87 is to close a circuit for the cathode 79 of the rectifier 72 through a portion of the secondary winding 93, energized, as before described, from the same transformer primary winding 47. The circuit may be traced from the grounded terminal 15, connected to one side of the cathode 79, by way of the conductor 117, through the switch arm 12 of the switch 87, and the contact member 119 in contact therewith in this position of the switch 87, to a tap 121 of the secondary winding 83. The circuit continues through the major portion of the secondary winding 83, by way of the conductor 123, to the other side of the cathode 79. In this "battery-operation" position of the switch 87, therefore, the battery 69 is connected to the primary winding 47 to charge the condensers 11 and 40, and to heat the cathode 79 of the rectifier 72.

In the position marked "A-C operation," the switch arms 10 and 19 engage open-circuit contact members, the switch arm 16 engages a contact member 131, and the switch arm 12 engages a contact member 125. The contact member 125 connects the complete secondary winding 83 to the cathode 79 by a circuit extending from the terminal 15, by way of the conductor 117, through the switch arm 12 of the switch 87 and the contact member 125 at this time in contact therewith, by way of a conductor 127, through the secondary winding 83, and by way of the conductor 123, to the cathode 79. The secondary windings 49 and 83 are then supplied with energy, through the further primary winding 75, from the alternating-current mains, through a connection made by the plug 71 and the wires 73. The connection may be traced from one terminal of the mains, by way of a conductor 129, the switch arm 16 of the switch 87 and the contact member 131 at this time in contact therewith, by way of a conductor 133, through the primary winding 75 and the condenser 135 in parallel and, by way of a conductor 137, back to the other side of the mains. In this position of the switch 87, therefore, the battery 69 is disconnected from the primary winding 47, and the instrument is operated by alternating current. When the switch 87 occupies its "battery-

charge" position, the same transformer 45 may be employed to recharge the battery 69, through the copper-oxide rectifier 145, from any source of alternating current, such as any of the standard 110-volt alternating-current outlets. This may be effected with the aid of a built-in self-contained full-wave-rectifying trickle charger. Recharging is not ordinarily necessary until after some two hundred consecutive exposure flashes, corresponding to four hours of continuous use, which permits a very large program.

In the position marked "battery charge," the switch arm 12 is open-circuited to disconnect completely the cathode 79. The primary winding 75 is connected to the alternating-current mains in the same way as before described, except that the switch arm 16 of the switch 87 makes contact, not with the contact member 131, but with a contact member 139 which, being permanently connected to the contact member 131, is likewise connected to the conductor 133. At this time, the switch arms 10 and 19 of the switch 87 make contact with contact members 141 and 143, respectively. Both contact members 141 and 143 are connected to the rectifier 145 and, through this rectifier, to the primary winding 47 of the transformer 45. The contact member 143 connects the full-wave copper-oxide rectifier 145 to opposite terminals of the primary winding 47, which is at this time supplied with energy through the primary winding 75, from the alternating current mains. One end of the copper-oxide rectifier is connected to one end of the transformer winding 47 by a conductor 147. The other end of the full-wave rectifier is connected to the other end of the transformer winding 47 through the switch arm 19 of the switch 87 and the contact member 143 at this time in contact therewith, by way of a conductor 20.

The intermediate tap 111 of the transformer winding 47 is connected, as before stated, by the conductor 113 to the grounded positive terminal of the battery 69. The negative terminal of the battery 69 is connected, by way of the conductors 101 and 151, the switch arm 10 of the switch 87 and the contact member 141 in contact therewith in this position of the switch 87, and by way of the conductor 153 to an intermediate point of the full-wave rectifier 145. By reason of these connections, the energy supplied to the transformer winding 47 by the primary winding 75 from the alternating-current mains is utilized in alternate cycles, through opposite halves of the winding 47 and corresponding portions of the full-wave rectifier 145, to charge the battery.

The battery-charging is thus effected when the switch is set at the "battery-charge" position. A charging rate of about one ampere is used, which charges the battery in eight to ten hours. The battery is easily inspected by removing a panel on the side of the box.

Modifications will occur to persons skilled in the art and all such are considered to fall within the spirit and scope of the invention, as defined in the appended claims.

What is claimed is:

1. Apparatus for use in flash-photography having, in combination, a camera, a gaseous-discharge flash-lamp mounted on the camera, a condenser connected to the flash-lamp to effect a discharge through the flash-lamp to produce an exposure flash, a battery, a vibrator, a transformer having a primary winding and a secondary winding, means for connecting the primary winding to the battery through the vibrator, means for connecting the secondary winding to the condenser to charge the condenser, a second transformer having a second primary winding and the said secondary winding, means for connecting the second primary winding to a source of alternating current at a time when the first-named primary winding is disconnected from the battery, and means for constituting the first-named primary winding as a secondary winding to the primary winding of the second transformer to charge the battery.
2. Apparatus for use in flash-photography having, in combination, a camera, a gaseous-discharge flash-lamp mounted on the camera, a condenser connected to the flash-lamp to effect a discharge through the flash-lamp to produce an exposure flash, a battery, a vibrator, a rectifier having a cathode, a transformer having a primary winding and two secondary windings, means for connecting the primary winding to the battery through the vibrator, means for connecting one of the secondary windings to the cathode to energize the cathode, means for connecting the other secondary winding to the condenser through the rectifier, a second transformer having a second primary winding and the said secondary windings, means for connecting the second primary winding to a source of alternating current at a time when the first-named primary winding is disconnected from the battery, a full-wave rectifier, means for connecting the first-named primary winding through the full-wave rectifier to the battery, and means for connecting the first-named primary winding to the second primary winding to charge the battery.
3. Apparatus for use in flash-photography having, in combination, a camera, a gaseous-discharge flash-lamp mounted on the camera, a battery, a vibrator, a transformer, a four-position switch in one position of which the circuits are disconnected, means operable when the switch occupies a second position for connecting the transformer to the battery through the vibrator to produce an exposure flash through the gaseous-discharge flash-lamp, means operable when the switch occupies a third position for effecting an exposure flash through the flash-lamp from a source of alternating-current energy, and means operable when the switch occupies its fourth position to connect the transformer to the source of alternating-current energy to charge the battery.
